UNITED STATES PATENT OFFICE.

CHARLES LONGENECKER, OF PHILADELPHIA, PENNSYLVANIA.

MECHANISM FOR FEEDING POWDERED MATERIAL.

Application filed September 29, 1921, Serial No. 504,130. Renewed April 5, 1924.

To all whom it may concern:

Be it known that I, CHARLES LONGENECKER, residing at Philadelphia, in the county of Philadelphia and State of Pennsylvania, a citizen of the United States, have invented or discovered certain new and useful Improvements in Mechanism for Feeding Powdered Material, of which improvements the following is specification.

- 10 In the form or construction of apparatus in which the pulverized fuel is moved from the tank or other source of supply along a pipe or conduit provided with successive ports or openings through which the fuel drops or is drawn, the powdered fuel is moved by the conveying screw so rapidly that a proper amount of fuel will not pass through the ports or openings into the branch pipes. The object of the invention 15 described herein relative to certain improvements in this class of apparatus whereby the powdered fuel may be fed to the branch pipes in substantially equal and uniform quantities.
- 20 In the accompanying drawings forming a part of this specification, Fig. 1 is a plan view showing a fuel supply hopper and means embodying the improvements claimed herein for moving the pulverized fuel from the hopper to the branch pipes leading to the burners; Fig. 2 is a view partly in elevation and partly in section of the construction shown in Fig. 1; Fig. 3 is a sectional elevation on a plane indicated by the line III—III, Fig. 2; Fig. 4 is a similar view, the plane of section being indicated by the line IV—IV, Fig. 3; Fig. 5 is a sectional view on a plane indicated by the line V—V, Fig. 3, and Fig. 6 is a view similar to Fig. 5 illustrating a modification of the construction shown in Fig. 5.

40 In apparatus for feeding pulverized fuel from a hopper through a conduit from which the pulverized material passes to branch pipes, it is customary to provide means for returning all powdered fuel which has not been diverted into the branch pipes to the hopper. In some of these systems, the branch pipes are connected to the conduit through which material passes while being fed out from the hopper. In other systems, the branch pipes are connected to what might be termed the return conduit. The former construction is shown and described in an application filed by me May 14, 1920, Serial No. 381,498, and the latter

system in another application filed by me August 5, 1920, Serial No. 401,310. As the latter form or construction is preferable in practical operation, the invention claimed herein is shown and described in connection with such form, but it will be understood that the broader claims are not limited to a construction in which the branches are supplied from the return conduit.

45 As described in application Serial No. 401,310, above referred to, the pulverized fuel is forced from the hopper 1 through the conduit 2 by the screw conveyor 3 at the outer end of this conduit 2, the powdered fuel drops through a passage 4 from which it is forced by a conveyor 5 through the return conduit 6 having its opposite end connected to the tank or hopper 1 at or near the lower end thereof.

50 At suitable points along the conduit 6, openings 7 are formed in the lower side of the conduit and into such openings project portions of shells 9 formed of metal and having slots 10 therein, said slots extending, when the shell is in position, under the conduit transversely of the latter. These shells are preferably screwed into tubular casings 11 having saddles 12 fitting around the conduit. At one end, these casings are provided with chambers A connected to a source of fluid under pressure, and their opposite ends are adapted to be connected to pipes 13 for conveying the fuel to the burners. Within these casings are arranged cylindrical valves 8 movable longitudinally in the shells to regulate the flow of powdered fuel through the slot 10 and adjustment is effected by means of threaded stems 14 secured to one end of the valves 8 and passing through rotatable nuts 15 mounted in the heads of the casings. On these nuts are secured operating pulleys 16 by the rotation of which the valves can be shifted back and forth in the shells 9. At their rear ends the valves are provided with ports 17 through which air supplied to the chamber in the casing by the pipes 18 will flow through the valves and into the branch pipes 13. It will be observed that by the longitudinal movement of these valves, not only will the flow of powdered fuel into the pipes 13 be controlled but also the flow of air through the valves and the pipe 13. It is preferred to so construct the valves that the ports 17 will be opened to allow the flow of air through the branches 13 before any portions of the slots 10 in the

shells 9 are opened to permit of the flow of powdered fuel into the branch pipes.

By reference to Figs. 2, 4, 5 and 6, it will be observed that the spiral blade forming a part of the conveyor 5 is not continuous but is made in sections 19 between which there is a substantial gap. The sectional conveyor is arranged in the conduit 6 so that the blade sections 19 are intermediate adjacent openings in the conduit in which the shells 9 are located and are made shorter than the distance between adjacent slots. It results from this construction that the only movement of the powdered fuel across the slots 10 will be due to the push of the section of the screw in advance of such slots and that the fuel is not swept across the slots while in contact with the blades and that the section of the screw in the rear of the slots will only take away as much of the fuel as may be forced to it by the feed of the prior section. In other words, by thus making the screw sections there will be a certain delay in the movement of the fuel above and adjacent to the location of the slots 10, thus affording the time for the flow of the fuel through such slots into the branches.

In order to insure the entrance of the powdered fuel into these slots, the wall of the shell in advance of the slot is cut away as indicated at *a*, Fig. 5. The surface of this cut away portion will, when the parts of the mechanism are adjusted together, be substantially flush with the bottom of the pipe or conduit 6. The opposite side of the slot will form an abutment *b* which will tend to check the movement of the fuel sliding along the bottom of the conduit and direct the powdered fuel down through the slot. 40 In lieu of the construction shown in Fig. 5 an ordinary slot may be formed in the shell and the latter may be so adjusted that one wall of said slot as *c* will be in a plane of the bottom of the conduit, as shown in Fig. 6.

It is characteristic of both of these constructions that the transverse area of the conduit will be restricted just at the rear of the slots thus causing a compacting of the material at that point and that this compacted material will by the pressure of the screw in front of the slots be forced down through the latter.

It is also characteristic of the improvement described herein that the powdered material will, while passing along the portions of the conduit in which the slots are located, move parallel with the axis of the conduit or at right angles to the slot, where-

as in former constructions wherein the blade 60 of the conveyor was continuous, the material moved angularly across the slots.

I claim herein as my invention:

1. The combination of an unobstructed conduit having a plurality of openings in 65 spaced relation in its lower side and a rotatable screw for moving the material along the conduit, the blade of the screw being formed in sections located intermediate adjacent openings and adapted to move forward material which will be passed beyond a preceding port.

2. The combination of a conduit having a plurality of openings in spaced relation in 75 its lower side, rotatable shells arranged at an angle to the axis of the conduit and so arranged in the openings that portions of the shells will extend into the conduit, the portions of the shells extending into the conduit being slotted, and a rotatable screw 80 for moving the powdered material along the conduit, the blade of the screw being formed in sections located intermediate adjacent shells.

3. The combination of a conduit having a 85 plurality of openings in spaced relation in its underside, shells arranged at an angle to the axis of the conduit and having portions extending into the conduit, the portions 90 extending into the conduit being slotted, a rotatable screw for moving powdered fuel along the conduit, the blade of the screw being formed in sections located intermediate adjacent shells, and valves for regulating the flow of powdered fuel into the 95 shells.

4. The combination of a conduit having a plurality of openings in spaced relation in 100 its underside, shells arranged at an angle to the axis of the conduit, and having portions extending through said openings into the conduit, such portions having slots, valves 105 controlling the flow of powdered material and air into said shells, means for shifting said valves, and a rotatable screw for moving powdered material along the conduit, the blade of the screw being formed in sections located intermediate adjacent shells.

5. The combination of a conduit, a plurality of slots in spaced relation transverse of 110 the conduit, abutments in the conduit in the rear of the slots, and a rotatable screw for moving material through the conduit, the blade of the screw being formed in sections located intermediate adjacent slots.

In testimony whereof I have hereunto set my hand.

CHARLES LONGENECKER.
